The ornamental design for a bottle, as shown and described.

DESCRIPTION

FIG. 1 is a front perspective view of a bottle showing my new design;

FIG. 2 is a front view thereof;

FIG. 3 is a back view thereof;

FIG. 4 is a side view thereof; and,

FIG. 5 is a top view thereof.

The broken lines in the Figures are for the purpose of illustrating unclaimed portions of the bottle and form no part of the claimed design.

The shade lines in the Figures show contour and not surface ornamentation.
